(57) **CLAIM**

The ornamental design for a light fixture including a pair of housings, as shown and described.

DESCRIPTION

FIG. 1 is a front perspective view depicting a light fixture including a pair of housings;

FIG. 2 is a front elevation view depicting the light fixture of FIG. 1;

FIG. 3 is a rear elevation view depicting the light fixture of FIG. 1;

FIG. 4 is a right side elevation view depicting the light fixture of FIG. 1;

FIG. 5 is a left side elevation view depicting the light fixture of FIG. 1;

FIG. 6 is a top plan view depicting the light fixture of FIG. 1;

FIG. 7 is a bottom plan view depicting the light fixture of FIG. 1; and,

FIG. 8 is a bottom perspective view depicting the light fixture of FIG. 1.

The details shown in broken lines in the figures form no part of the claimed design of the light fixture including a pair of housings. Any details shown in dot-dash broken lines in the figures define the bounds of a portion of the claimed design of the light fixture including a pair of housings and form no part of the claimed design. The figures include surface shading, which represents contour and not surface ornamentation.
